REINHOLD SCHOELL, OF STAMFORD, CONNECTICUT, ASSIGNOR TO THE YALE & TOWNE MANUFACTURING COMPANY, OF STAMFORD, CONNECTICUT.

LOCKING DEVICE FOR CIRCUIT-CONTROLLING MEANS.

1,142,732.

Specification of Letters Patent. Patented June 8, 1915.

Application filed August 15, 1914. Serial No. 856,954.

To all whom it may concern:

Be it known that I, REINHOLD SCHOELL, a citizen of the United States, and resident of Stamford, in the county of Fairfield and 5 State of Connecticut, have invented certain new and useful Improvements in Locking Devices for Circuit-Controlling Means; and I do hereby declare the following to be a full, clear, and exact description of the invention, such as will enable others skilled 10 in the art to which it appertains to make and use the same.

This invention relates to locking devices for circuit controlling means, and more particularly to such as are adapted to control the circuit of the sparking or timing mechanism of internal combustion engines for automobiles and the like,—one object of the invention being to provide simple and efficient 20 means for safeguarding automobiles by locking the devices which control the circuit connections, especially for cars equipped with low tension magnetos, spark coil and timer similar to the Ford car (Model T) construction. 25

A further object is to so construct the device that it may be readily applied to the car, either by the manufacturer, or by the owner after the car has been used.

30 With these and other objects in view, the invention consists in certain novel features of construction and combinations of parts as hereinafter set forth and pointed out in the claims.

35 In the accompanying drawings; Figure 1 is an inner face view, with the base block removed; Fig. 2 is a face view of the base block; Fig. 3 is an end view of said base block; Fig. 4 is a side elevation of the assembled device; Fig. 5 is a longitudinal view; 40 Fig. 6 is a sectional view taken at right angles to Fig. 5; Fig. 7 is a transverse sectional view on the line 7—7 of Fig. 6, and Figs. 8 and 9 are face views, showing the two positions to which the lock plug may be moved.

1 represents a base block which may be made of fiber or other electrical insulating material, and is provided at its respective 50 ends with notched flanges 2 for the accommodation of the wires which form parts of an electric circuit for effecting the operation of timing or other electrical mechanism. The said wires are clamped between the 55 notched flanges of the base block and

notched blocks 3 of insulating material mounted within a metal casing 4, the clamping of the wires being effected by means of screws 5 passing through said casing and entering interiorly threaded thimbles 6 connected with the base block and projecting into holes 7 in the blocks 3, as clearly shown in Fig. 6. The insulation is removed from those portions of the electric wires 8 which pass between the insulating clamping 65 blocks so that the naked wires will be exposed for engagement therewith of a spring contact plate 9, whereby the current in said wires may be short-circuited for the purpose of rendering inactive, the timing or other 70 mechanism which said current is intended normally to actuate or control. The contact spring plate 9 is fluted or corrugated as shown in Fig. 6 and is secured at one edge between one of the blocks 3 and the casing 4. 75

A barrel 10 is secured rigidly to the casing 4 and contains a lock cylinder 11, in which the plug 12 of the lock is mounted. The plug 12 is provided with the usual key slot, and two sets of pin tumblers are mounted in radial flanges 13 on the lock cylinder for locking the plug in either of two positions to which it may be moved. A cam 14 is secured to one end of the lock plug 12, so that when said plug is turned in one direction (with the use of a proper key), said cam will engage the fluted or corrugated contact plate 9 and force the same into electrical contact with the wires 8, thus short-circuiting the source of electrical energy and thereby rendering inoperative, the timing or other electrically actuated means. It is apparent that the parts will be locked in such inoperative relation when the key shall have been removed from the plug of the lock. 80 With the use of the key, the plug may be unlocked, and turned in the reverse direction, when the cam 14 will be so moved with relation to the contact plate that the resilience of the latter will cause it to move out of engagement with the wires, and thus establish normal operative conditions. The turning of the plug in each direction may be limited by means of stop pins 15—16, with which the cam 14 engages. 85

90 My improvements are particularly designed for use in protecting internal combustion engines of automobiles, against unauthorized use.

95 After the device shall have been clamped 110

to the timing wires as above explained, the barrel 10 may be passed through a suitable hole in the dash of an automobile and a knurled nut 17 will then be screwed on the inner end of said barrel and made to bear against the inner face of the dash, thus clamping the device to said dash. The annular nut 17 is made internally with a beveled wall 18 to be engaged by a pin 19 movably mounted within the inner portion of the barrel 10. The head of this pin is made partially conical and is engaged by the conical portion of a screw 20 which enters the head of the cylinder. With such construction, the annular nut 17 will be locked in place, and when the lock-plug shall have been so turned as to force the short-circuiting spring 9 into contact with the wires 8, the screw 20 will be covered by a pointer finger 21 rigidly secured to the lock-plug 12.

With the use of my improvements, it is apparent that when the timing or other wires are short-circuited and the key has been removed from the lock, it will be impossible to render the circuit operative otherwise than with the use of a proper key, and that as the screw 20 which controls the locking of the nut 17 to the barrel will be covered by the finger 21 on the lock barrel, removal of the device to free it from the wires, cannot be effected.

My improvements are simple in construction; effective in operation to control the operation of electrical devices; may be easily applied, and will be efficient in preventing unauthorized tampering with the electrical controlling mechanism which they are designed to protect.

Slight changes might be made in the details of construction of my invention without departing from the spirit thereof or

limiting its scope, and hence I do not wish to restrict myself to the precise details herein set forth.

Having fully described my invention what I claim as new and desire to secure by Letters-Patent, is:—

1. In a device of the character described, the combination of a support, a barrel, a lock mounted therein, clamping means for electric wires secured to said barrel, a contact device in said clamping means, a cam on a movable part of the lock for moving said contact device, a nut on the free end of said barrel for securing the device to the support, means for locking said nut against removal, and means on a movable part of the lock for protecting the locking means for the nut when the contact device has been operated to electrically connect said wires.

2. In a device of the character described, the combination of a support, a barrel, clamping means for electric wires secured to said barrel, a contact device for said wires mounted in the clamping means, a lock located in the barrel, a cam carried by a moving part of the lock for actuating said contact device to connect said electric wires, an annular nut on the barrel for securing the device to the support, a locking pin for said nut mounted in the barrel, a screw in the head of the barrel for moving said locking pin, and a finger on a moving part of the lock for covering said screw when the contact device connects said electric wires.

In testimony whereof, I have signed this specification in the presence of two subscribing witnesses.

REINHOLD SCHOELL.
